UNITED STATES PATENT OFFICE.

JOSEPH W. HOWGATE, OF WILMINGTON, DELAWARE.

THILL-COUPING.

SPECIFICATION forming part of Letters Patent No. 417,642, dated December 17, 1889.

Application filed October 2, 1889. Serial No. 325,738. (No model.)

To all whom it may concern:

Be it known that I, JOSEPH W. HOWGATE, a citizen of the United States, and a resident of Wilmington, in the county of New Castle 5 and State of Delaware, have invented certain new and useful Improvements in Thill-Couplings; and I do hereby declare that the following is a full, clear, and exact description of the invention, which will enable others 10 skilled in the art to which it appertains to make and use the same.

My invention relates to improvements in that class of devices known as "anti-rattling thill-couplings," the object being to provide 15 a cheap, simple, durable, and reliable coupling in which the wear of the parts may be readily taken up and compensated for, thus obviating the disagreeable and injurious rattling incident to all thill-couplings which are unprovided 20 with any means for preventing the same.

Many attempts have heretofore been made to provide a thill-coupling of the type named above which would be simple in operation, cheap in manufacture, reliable and durable 25 in use, and which would perform its object in an efficient manner. Such attempts, however, have generally proved failures, and the devices have not gone into extensive public use. This is due to inherent defects in construction and operation, which my invention 30 is designed to obviate.

My invention consists in the several novel features of construction and new combinations of parts, hereinafter fully described, and 35 definitely pointed out in the appended claims.

In the accompanying drawings, Figure 1 is a central longitudinal section through one of the couplings. Fig. 2 is a top or plan view of the same. Fig. 3 is a perspective view of the 40 slotted flanged clamp or holder to which the thill-iron is connected, and Fig. 4 is a perspective view of the eccentrically-headed bolt which secures the thill-iron to the clamp.

In the said drawings the reference-numeral 45 1 designates the axle, and 2 the usual clip by which the shackle of the coupling is secured thereto. This shackle consists of a metallic body having two forwardly-projecting ears or lugs 3, each of which is perforated for the 50 reception of a bolt 4, and the rearwardly-extending plate 5, which has perforations in

front and rear of the axle for the screw-threaded ends 6 6 of the clip, which receives the nuts 7, by which the shackle is securely connected with the axle. The clamp or holder 55 8, to which the thill-iron is connected, consists of a metallic plate bent over upon itself at the center, forming two parallel portions 9, which at their forward ends are turned outwardly, forming flanges 10. This clamp or 60 holder is inserted between the ears 3 3 of the shackle, and the bolt or pin 4 is inserted through the apertures in the ears and is embraced by the bent-over portions of the clamp, the interior surface of the bend of the clamp 65 resting against said bolt, and thus securely connected with the shackle.

The portions 9 of the clamp are provided with two oblong or oval slots or apertures 11, which coincide or register with each other, as 70 seen in Fig. 3. 12 designates the pole or thill iron having an aperture near its rear end, and 13 the bolt by which the same is connected by means of said aperture with the clamp. This bolt consists of a shank screw-threaded at its 75 lower portion to receive the nut 14. This bolt is provided at its upper end with an eccentric head 15, having a nick 16 for the reception of an ordinary screw-driver. This head 15 consists of a circular disk, with the 80 bolt-shank a little to one side of the center thereof, said head thus forming an eccentric or cam. The bolt 4 is made from steel and is designed to fit snugly within the apertures in the ears 3; but for further security against 85 accidental displacement the pin or bolt 17 may be provided, extending vertically through one of the ears 3 above the bolt 4 and engaging with the latter.

From the above the operation of the device 90 will be readily understood. The shackle being securely connected with the axle by means of the clip, the clamp is inserted between the ears 3 and the bolt 4 passed through the apertures therein, thus holding the clamp 95 in place. The thill or coupling iron 12 is then inserted in the clamp, and the bolt 13 passed through the oval slots or apertures therein and the aperture in the thill-iron. The eccentric head of the bolt is then turned by 100 means of a screw-driver till it abuts firmly against one of the flanges 10 of the clamp.

The nut 14 is then screwed home on the bolt, and the parts are all thus securely held and rattling prevented. It will be obvious that any wear of the parts 5 may be readily compensated for or taken up by means of the oval slots in the shackle and the eccentrically-headed bolt, the oval slots allowing a slight horizontal movement of the thill-irons when the bolt is unloosened for the purpose of adjusting said irons on account of wear.

Having thus described my invention, I claim and desire to secure by Letters Patent of the United States—

1. The combination, with a thill-coupling, of the clamp or holder consisting of a metal plate bent over at its center, forming two parallel portions provided with oval or oblong

apertures and having its ends bent outwardly to form flanges, and the bolt passing through said apertures and having an eccentric head, substantially as described.

2. The combination, with the shackle having the ears 3, the bolt 4, and the thill-iron 12, of the clamp 8, having oblong apertures 25 11 and flanges 19, the bolt 13, having eccentric heads 15, with nick 16, and binding-nut 14, substantially as described.

In testimony that I claim the foregoing as my own I have hereunto affixed my signature in presence of two witnesses.

JOSEPH W. HOWGATE.
